UNITED STATES PATENT OFFICE.

JEROME R. BUCHANAN AND ROBERT H. ABBOTT, OF LOS ANGELES, CALIFORNIA.

DESIGN FOR A BALL LAMP ADAPTER FOR LIGHTING FIXTURES.

Application filed December 12, 1925. Serial No. 15,733. Term of patent 7 years.

To all whom it may concern:

Be it known that we, JEROME R. BUCHANAN and ROBERT H. ABBOTT, citizens of the United States, both residing at Los Angeles, in the county of Los Angeles and State of California, have invented a new, original, and ornamental Design for Ball Lamp Adapters for Lighting Fixtures, of which the following is a specification, reference

being had to the accompanying drawing, forming part thereof.

Figure 1 is a front view, and Figure 2 is a side view.

We claim:

The ornamental design for a ball lamp adapter for lighting fixtures as shown.

JEROME R. BUCHANAN.
ROBERT H. ABBOTT.
